UNITED STATES PATENT OFFICE.

PATRICK DEEVY, OF DUDLEY, IOWA.

WHEELED SCRAPER.

SPECIFICATION forming part of Letters Patent No. 364,493, dated June 7, 1887.

Application filed June 8, 1886. Serial No. 204,468. (No model.)

To all whom it may concern:

Be it known that I, PATRICK DEEVY, of Dudley, in the county of Wapello and State of Iowa, have invented a new and Improved 5 Wheeled Scraper, of which the following is a full, clear, and exact description.

My present invention relates to the construction of that class of scraper illustrated, described, and claimed in my application, No. 10 167,897, filed on the 6th day of June, 1885; and the invention consists of certain improvements upon the construction illustrated in said application, which improvements will be hereinafter more fully described, and specifically 15 pointed out in the claims.

Reference is to be had to the accompanying drawings, forming a part of this specification, in which similar figures of reference indicate corresponding parts in all the figures.

20 Figure 1 is a plan view of my improved form of scraper, certain portions being shown in section. Fig. 2 is a side view of the scraper, representing the parts as they appear when the bowl is depressed to the position it assumes 25 when being filled, the wheel upon the side of the scraper illustrated being, however, removed. Fig. 3 is a side view of the scraper, illustrating the parts as they appear after the bowl has been raised to a position so that the 30 load gathered while in the position in which the parts are illustrated in Fig. 2 may be removed to the spot where it is desired to dump the load; and Fig. 4 is a side view of the 35 scraper, the parts being shown in the position they assume after the load has been dumped, this being the position to which the bowl is moved when it is desired to move the unloaded scraper from place to place.

The scraper-bowl 100 is made in the general 40 form of a scoop, the rear of the bowl being, however, stiffened and strengthened by a malleable-iron casting, 10, that is riveted to place about the rear inner and upper edge of the bowl, as best shown in Fig. 1. To the sides 45 of the bowl there are riveted suspending arms 11, the upper ends of which are formed with sockets 12, through which the horizontal central portion, 13, of the axle passes, collars 14 being formed on said axle in position so as to 50 properly space and prevent any side movement of the sockets 12 of the suspending arms

11. Just outside of the sockets 12 there are secured the crank-arms 15 of the axle, said crank-arms being formed with sockets at their upper end, within which the ends of the axle 55 13 are inserted, the parts being keyed together as shown in the drawings.

The crank-arms 15 carry the journals 16, upon which the wheels 20 are mounted. The journals 16, upon which, as just stated, the 60 wheels 20 are mounted, carry hoods 17, that are keyed to the inner ends of the journals and project outward over the hubs 18 of the said wheels 20, serving to protect the journals from sand, dirt, or grit of any kind.

Upon each side of the bowl 100 I secure an outwardly-extending bracket, 19, to which the rear ends of the draw-bars 21 are pivotally connected through the medium of bolts 22, the brackets 19 being so formed that the draw-bars 70 75 will be at some distance from the sides of the scraper-bowl. The draw-bars are of peculiar form, being provided with a rearwardly-extending lug or ear, 23, by means of which pivotal connection with the brackets 19 is established, said lug or ear extending backward from the upper end of a substantially vertical portion, 24. From the lower end of the portion 24 the draw-bars curve forward and then upward and forward, this upward and forward 80 extending portion being riveted or otherwise secured to the main cross-bar 25, against the forward face of which the pole 26 abuts, the stock of said pole entering between angle-irons 27, that are secured to the cross-bar 25, as best 85 shown in Fig. 1.

Just in front of the cross-bar 25 the draw-bars 21 extend inward until they strike the side of the pole 26, and at that point they are bent forward, and their ends 28 so bent forward 90 are firmly bolted to the pole.

At the rear of the scraper-bowl there is arranged the main operating-lever 30, said lever being provided with two outwardly-branching arms, 31, which extend forward a short distance in diagonal lines as they leave the lever 30, and then extend outward at right angles to the lever in the same horizontal plane, to be bent so as to extend forward in parallel lines at 32, said forward parallel extending 100 portions being shown at 36. To the arms 31 there is secured a bar, 33, formed with two for-

wardly and downwardly extending arms, 34, the lower ends of which are pivotally secured to the sides of the bowl 100 by brackets 35. As best shown in Fig. 1, the arms 34 are arranged so that between their outer faces and the forwardly-extending portion 36 of the arms 31 there is a space, and in this space so formed there are arranged connecting-rods 37, said rods being pivotally mounted through the medium of bolts 38.

The forward ends of the connecting-rods 37 are pivotally connected to rearwardly-extending and slotted lugs 39, formed upon the crank-arms 15, the forward ends of the connecting-rods 15 entering the slot formed in said lug 39.

From the construction just described it will be seen that the scraper-bowl is hung so as to swing upon the horizontal portion of the axle of the scraper, and it will also be seen that the angle at which the bowl hangs depends upon the length of the connecting-rods 37, and consequently in order that this angle may be varied I have formed said connecting-rods with a number of holes, 2, through any one of which the bolts 38 may be passed, in order that the bowl may be adjusted as required.

Projecting to the rear of the scraper-bowl there are handles 40, said handles being riveted to the sides of the bowl, and to the center 30 of the rear end of the bowl there is pivotally connected a catch, 41, that is provided with a rearwardly-extending handle, 42, said catch being formed with an upper inclined face, 43, against which the central portion of the cross-bar 33 strikes when the lever 30 is being thrown to the position in which it is shown in Fig. 3. The throw of the lever 30 is limited by a stop, 5, which projects to the rear from the scraper-bowl 100. Upon being struck the catch will 40 be thrown toward the bowl, permitting the bar 33 to pass, and after the bar is below the tooth of the catch the handle 42 will act to throw the catch to the rear, so that it will engage with the upper face of the said bar 33.

45 In order that the bowl may be held in a fixed position when lowered to the position in which it is shown in Fig. 2, I have provided such an attachment as will now be specifically described. To each side of the bowl 100, and 50 near the forward edge of said bowl, there is rigidly secured a bracket, 45, which serves as the support for a pivotally-mounted lever, 46, to one end of which there is secured an outwardly-projecting pin, 47. The opposite and 55 lower ends of the levers 46 are connected by links 49 to the lower ends of lugs 50, formed upon the arms 34 of the bar 33.

In connection with the pin-carrying levers 46 I arrange oscillating strips 52, in the rear 60 ends of which there are formed flaring bell-shaped slots 53. The strips 52 are made integral with practically vertical strips 54, that fit close against the inner faces of the draw-bars 21, the upper end of each strip being bent 65 to form ears 55, which overlap the upper edges of the said draw-bars. The lower ends of the strips 54 are bent outward beneath the draw-

bars 21, to form lugs or ears 56, and in these lugs or ears 56 I make threaded sockets, in which there are mounted adjusting-screws 57. 70

Referring now to Fig. 2, it will be seen that as the bowl 100 is lowered the lugs 50 will be thrown back, and, drawing upon the connecting rods or links 49, will throw the upper ends of the levers 46 forward, so that their pins 47 75 will enter the bell-shaped slots 53, formed in the oscillating strips 52, and consequently when the parts are in the position shown in the figure referred to—that is, when the bowl is being loaded—all possibility of the accidental dumping of the bowl will be avoided; also, a certain amount of play will be permitted, owing to the fact that the strips 52 are free to oscillate within certain limits.

When it is necessary to transport the scraper 85 from place to place, it is desirable that the bowl should be moved to a position in which it will be held above the ground, so as not to require any particular attention from the driver; and to meet these requirements I have provided a 90 catch, 60, that is pivotally mounted in a standard, 61, and normally held in the position in which it is shown in the drawings by the action of a spring, 62, one end of which is rigidly fixed to the catch-arm, while the other 95 presses against the inner upper face of the recess, within which the catch is pivotally mounted. From its catch-tooth 63 the catch projects upward in a diagonal line to the rear, thus forming a handle, 64, and at the same time providing for the automatic lifting of the catch when the bowl is to be thrown to the position in which it is shown in Fig. 4, for as the bowl is raised to the position indicated one of the arms 31 will strike against the inclined face of the handle 64, and the catch will be raised against the tension of the spring 62 until its catch-tooth 63 has been brought into engagement with the flange 3 of the stop or projection 5, that is secured to the rear end of the 100 scraper-bowl, as above stated.

Having thus fully described my invention, what I claim as new, and desire to secure by Letters Patent, is—

1. The combination, with a wheeled scraper 115 having the crank-axle, and the pivoted bowl provided with locking-levers at or near the forward ends of its sides, of the draw-bars pivotally connected with the bowl and having locking-strips constructed to be engaged by the said locking-levers, and the manipulating-lever connected to the bowl, links connecting the said lever and the crank-axle and also connecting said lever and the locking-levers, substantially as set forth. 125

2. In a wheeled scraper, the combination, with a crank-axle, of a suspended scraper-bowl, a manipulating-lever, the ends of which are pivotally connected to the scraper-bowl, and a link formed with a number of apertures and arranged to connect the lever and the axle, substantially as described. 130

3. In a wheeled scraper, the combination, with a crank-axle, of a scraper-bowl connected

thereto by suspending arms, a manipulating-lever pivotally connected to the bowl and connected to the axle by a link, draw-bars pivotally connected to the bowl, slotted vibrating

strips carried by the draw-bars, levers carrying pins arranged to enter the slots in the vibrating strips, said levers being pivoted to the scraper-bowl, and links connecting said pin-carrying levers with the main manipulating-lever, substantially as described.

4. In a wheeled scraper, the combination, with a crank-axle, of a scraper-bowl connected thereto by suspending arms, a manipulating-lever pivotally connected to the bowl and connected to the axle by a link, draw-bars pivotally connected to the bowl, slotted vibrating strips carried by the draw-bars, adjusting-screws carried by the vibrating strips, levers carrying pins arranged to enter the slots in the

vibrating strips, said levers being pivoted to the scraper-bowl, and links connecting said pin-carrying levers with the main manipulating-lever, substantially as described.

5. In a wheeled scraper, the combination, with a scraper-bowl mounted as described, of draw-bars 21, pivotally connected to brackets 19, immovably secured to opposite sides of the bowl, the said draw-bars being formed with rearward-extending ears 23, and extending downward, as shown at 24, and then upward 30 and forward, substantially as described.

6. In a wheeled scraper, a scraper-bowl having a re-enforcing strip, 10, riveted to the scraper-bowl, substantially as described.
